UNITED STATES PATENT OFFICE

157,900

IRRIGATING APPARATUS

Edmond O. Pratt, Los Angeles, Calif.

Application October 18, 1947, Serial No. 142,005

Term of patent 7 years

(Cl. D83—1)

To all whom it may concern:

Be it known that I, Edmond O. Pratt, a citizen of the United States, residing in the city of Los Angeles, county of Los Angeles, and State of California, have invented a new, original, and ornamental Design for an Irrigating Apparatus, of which the following is a specification, reference being had to the accompanying drawings, forming a part thereof.

Fig. 1 is a perspective view of the irrigating apparatus, showing my new design, taken from the front and one side thereof, and Fig. 2 is a perspective view of the apparatus taken from the rear and the other side thereof.

I claim:

The ornamental design for an irrigating apparatus, as shown.

EDMOND O. PRATT.
